UNITED STATES PATENT OFFICE.

THEODOR HOLZHALB, OF BROOKLYN, NEW YORK, ASSIGNOR TO THE SEGAR STUDIOS INC., A CORPORATION OF NEW YORK.

DESIGN FOR A WALL BRACKET.

Application filed September 10, 1926. Serial No. 19,023. Term of patent 7 years.

To all whom it may concern:

Be it known that I, THEODOR HOLZHALB, a citizen of the United States, and a resident of the city of Brooklyn, county of Kings, and State of New York, have invented a new, original, and ornamental Design for a Wall Bracket, of which the following is a specification, reference being had to the accompanying drawing, forming a part hereof.

The figure in the drawing shows a front elevational view of the wall bracket.

I claim:

The ornamental design for a wall bracket, substantially as shown.

THEODOR HOLZHALB.
